Patented Dec. 26, 1922.

UNITED STATES PATENT OFFICE.

GEORGE V. CLINK, OF ST. PAUL, MINNESOTA.

GAME.

Application filed August 23, 1921. Serial No. 494,462.

To all whom it may concern:

Be it known that I, GEORGE V. CLINK, a citizen of the United States, residing at St. Paul, in the county of Ramsey and State of Minnesota, have invented a new and useful Game, of which the following is a specification.

This invention relates to games and toys, and more particularly to a score keeping device employed in connection with a game board for recording the scores of the game.

The primary object of the invention is to provide a score keeping device in the form of a base-ball field, novel means being provided for indicating the positions of the runners during an inning of the game.

Another object of the invention is to provide means for recording the scores of the innings.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 is a plan view of the score board.

Figure 2 is a plan view of the board, the cover or top thereof being removed.

Figure 3 is a sectional view taken on line 3—3 of Figure 2.

Figure 4 is a sectional view taken on line 4—4 of Figure 2.

Figure 5 is a plan view of the game board to be employed in connection with the score keeping board.

Referring to the drawings in detail, the score keeping board which forms the essence of the invention, embodies a box-like structure including the bottom member 5, side walls 6 and end walls 7. Positioned within the box-like structure to divide the interior thereof into compartments, is a partitioning wall 8.

Extending transversely of one of the compartments, is a shaft 9 on which is positioned a tubular bearing member 10 which supports the arms 11, 12 and 13 respectively, the arms 11, 12 and 13 being mounted on the member 10 to permit the same to oscillate within the compartment.

Each of these arms carries an upwardly

extending bar 14 on which is positioned a game piece 15 in the form of a runner, the bars 14 being secured to the arms 11, 12 and 13 in a manner to cause the game pieces to extend to positions above the top or cover piece 16, when the arms are operated. As clearly shown by Figure 1 of the drawings, the top or cover piece 16 is marked in a manner to simulate a baseball diamond, openings being formed in the cover piece 16 at predetermined positions to represent the various bases, the openings also being provided to accommodate the bars 14 to permit the bars to extend therethrough and project the game pieces carried thereby, above the top or cover piece 16 to indicate the position of a runner.

A controlling bar 17 has connection with each of the arms 11, 12 and 13, it being understood that a controlling bar is carried by each of the arms, the controlling bars being of lengths to extend through the top or cover piece 16, so that when the game pieces 15 are in positions below the top or cover piece 16, the controlling bars 17 are extended to positions above the top or cover piece 16 where they may be moved by the operator to extend the game pieces above the top or cover piece 16 to carry out the principles of the board.

The opposite compartment houses a plurality of disks 18, which carry suitable members which may be moved under the openings 19 formed in the cover piece to indicate "outs", "balls" and "strikes". Associated with the disks 18 is a disk 20 which also has numbers disposed thereon, the numbers being positioned on the disk 20 to move under the opening 21 to indicate the number of runs made. These disks have portions of their peripheries extending beyond the side and end wall of the device so that the disks may be engaged by the finger of the operator to rotate the same to cause the members to appear below the openings in the top or cover piece 16.

Employed in connection with the score board, is a game board shown more particularly by Figure 5 of the drawings, the game board being indicated by the reference character 22 and is provided with an upwardly extending flange 23 to prevent the ball 24 which forms a part of the game board from being forced off of the board.

Extending upwardly from the board 22 and arranged in staggered relation with re-

spect to each other, are the pins 24 which act to obstruct the movements of the ball 24 in its passage to the pockets or compartments formed by the pins. The ball 24 is moved 5 by the plunger 25 which operates between one wall of the game board and the partitioning wall 26, the ball 24, in its set position, being held at a point opposite the spring bar 27 which is disposed at an angle 10 across one corner of the game board and lies directly in the path of travel of the ball 24 when the same is forced from its set position.

Assuming that the ball 24 is moved and 15 the same passes between the pins and falls in the pocket or compartment labeled "two base hit", one of the controlling bars 17 is operated to move the game piece under the second base, to a position above the upper 20 surface of the top or cover piece 16, thus indicating that a man is on second base. Should the ball 24 be moved and fall into the pocket labeled "out", one of the disks 18 is operated to move a number 1 directly 25 under the opening 19 opposite the mark "outs".

It is believed that in view of the foregoing the operation and use of the score board in connection with the game board as shown 30 by Figure 5 will be obvious, it being understood that the movements of the ball 24 are recorded in a manner as described.

Having thus described the invention what is claimed as new is:—

35 1. A score board including a box-like structure, a partition for partitioning the

interior of the box-like structure into compartments, oscillating arms within one of the compartments, a cover piece having openings, bars carried by the arms and adapted 40 to extend through the openings, and controlling bars carried by the arms and adapted to be moved to cause the bars to extend above the cover piece.

2. A score board including a box-like 45 structure, means for dividing the box-like structure into compartments, arms within one of the compartments, a cover piece having openings, bars carried by the arms, and adapted to move through the openings, 50 means carried by the arms for moving the arms, and said bars carrying game pieces.

3. A score board including a box-like structure, a partition for dividing the box-like structure into compartments, a rod extending transversely of one of the compartments, arms pivotally held and supported on the rod at points intermediate their ends, 55 bars carried by the arms and adapted to move therewith, a cover piece having openings, said openings being disposed directly over the bars to permit the bars to extend therethrough, and controlling bars for operating the arms.

In testimony that I claim the foregoing 60 as my own, I have hereto affixed my signature in the presence of two witnesses.

GEORGE V. CLINK.
